UNITED STATES PATENT OFFICE.

ALBERT BALL, OF CLAREMONT, NEW HAMPSHIRE, ASSIGNOR, BY MESNE ASSIGNMENTS, TO SULLIVAN MACHINERY COMPANY, OF BOSTON, MASSACHUSETTS, A CORPORATION OF MASSACHUSETTS.

MINING-MACHINE.

1,185,276.

Specification of Letters Patent.

Patented May 30, 1916.

Application filed August 4, 1906. Serial No. 329,190.

To all whom it may concern:

Be it known that I, ALBERT BALL, a citizen of the United States, residing at Claremont, in the county of Sullivan and State of New Hampshire, have invented an Improvement in Mining-Machines, of which the following description, in connection with the accompanying drawings, is a specification, like letters on the drawings representing like parts.

My invention relates to mining machines and more particularly to machines of the cutter chain type which are fed along the face or side of the wall in which the cut is being made.

Among the objects of my invention are improved means for controlling and handling such machines and various improved constructional features which provide a machine of compact form, great strength and effectiveness, and convenience of arrangement.

My invention will be best understood by reference to the following description when taken in connection with the accompanying illustration of one specific embodiment thereof, while its scope will be more particularly pointed out in the appended claims.

- 30 In the drawings, Figure 1 is a plan view of a mining machine embodying one form of my invention with the exterior casing removed, and showing the cutter bar thereof partially broken away; Fig. 2 is a side elevation of the same machine with the rear portion of the casing removed to show the operating parts; Fig. 3 is a sectional elevation on an enlarged scale taken through the fore part of the machine and showing the power transmission devices for the cutting mechanism; Fig. 4 is a plan view also on an enlarged scale of the opposite end of the machine and showing in plan the feed transmission gearing; Fig. 5 is a sectional elevation taken on the line 5—5 in Fig. 1 showing the locking mechanism for the cutter bar; Fig. 6 is a diagrammatic plan of the machine showing the connections to the feeding chain when it is employed for cutting in a reverse direction; Fig. 7 shows in perspective the machine body or frame with the outer casing in position; Fig. 8 is a section

on the line 8—8 in Fig. 4 showing the construction of the valve-crank shaft; Fig. 9 is a sectional elevation on the line 9—9 in Fig. 8 showing the clutch members on the crank shaft in one relation; Fig. 10 is a similar view showing them in another relation; Fig. 11 shows in perspective the valve reversing wrench; Fig. 12 is a plan view of the yieldable transmission device for the feed gearing; Fig. 13 is a transverse sectional elevation of the machine taken through the said transmission device; Fig. 14 is a section taken on the irregular line 14—14 in Fig. 1 showing the feed transmission gearing; Fig. 15 shows the cam slide-rod; Fig. 16 one of the clutch gear sleeves, Fig. 17 the other clutch gear sleeve. Fig. 18 is a central section in elevation, partly broken away, taken through one of the engine cylinders and showing the relation of the exhaust passages of such cylinder to the machine casing; Fig. 19 is a sectional elevation looking from the end of the machine and showing the guide roll k^2 ; Fig. 20 is a sectional detail in elevation taken through the locking bolt f^{12} for the cutter bar; Fig. 21 is a sectional detail taken transversely through the gear frame G and its elevating crank and crank pin; and Fig. 22 is a sectional plan view taken on the line 22—22 of Fig. 17 and showing the air-receiving chamber C.

In the drawings I have shown, for the purpose of illustrating the various features of my invention, an air driven chain mining machine of the so-called "long-wall type", that is to say, a machine which is adapted to make a continuous cut while traveling close to the face of the wall, the top of the mine being either posted or permitted to drop except in the narrow space in which the machine travels.

In the particular type of machine illustrated there is provided a cutter bar with cutting mechanism which during the cutting operation is swung to approximately a right-angled relation to the body of the machine. The cutting mechanism is driven through suitable transmission devices by a pair of fluid pressure engines which are also connected to actuate suitable feeding mechanism for the simultaneous traverse of the

machine under its own power. In the specific type of machine shown the machine is caused to slide along the mine bottom upon a suitable bottom plate or shoe and without the necessity of tracks or other like guiding devices, the feeding taking place through appropriate engagement with a stationary feeding chain having its opposite ends anchored along the face of the wall and in accordance with the general principles disclosed in U. S. patent to Mitchell No. 656,414. It is to be understood however, that while certain features of my invention herein disclosed relate more particularly to fluid pressure operated mining machines, and others to machines of the long-wall type, yet in many of its features and combinations it has, and is intended to have, general and broad application to mining and other machines of quite dissimilar types.

Referring to the drawings and to the specific embodiment of the invention there shown, the principal operative parts are mounted on and firmly secured to an underlying frame member consisting of the flat bottom plate or shoe A. In the described machine this is constructed of wrought iron and extends substantially the entire length and breadth of the main body of the machine so as to underlie the same and form a firm and solid support therefor during its sliding contact with the mine bottom.

Mounted on the bottom plate and securely fastened thereto, as by rivets or the like, is the main engine frame or casting B in which are formed the engine cylinders and on which are supported the bearings for the crank shaft, the feed transmission gearing and other power-transmitting parts. There are here provided two engines arranged side by side having the cylinders b, b and valve chambers b', b' formed on top of the cylinders. In the present instance the main engine casting (Fig. 4) is split into two separate parts along an intermediate plane, the two parts, however, being bolted together and the cylinders being joined together by a frame portion which is cored out to form an air receiving chamber C. The cored portions of the two separated frame members are in free communication with each other through a passage c (Figs. 4 and 22) forming in effect a single receiving chamber of appreciable volume as compared with that of the cylinders, having preferably as herein a cubical capacity not less than that of the two cylinders combined. The receiving chamber has free connection with the live pressure ports in the valve chambers through passages not here shown, and has an exterior valve-controlled admission conduit c' which may be connected to any suitable source of live pressure, as through the flexible hose connection c² (partially shown in Fig. 4).

The receiving chamber C maintains an even supply pressure for the engines irrespective of their pulsations, and is of marked advantage particularly in this type of traveling mining machine where the larger sizes of hose are so stiff and heavy that owing to the difficulty in handling they are usually dragged along the mine bottom as the machine is moved, resulting in injurious wear. The receiving chamber permits the effective operation of the engine with a smaller supply hose than could be used were the pressure supplied to the valve chambers directly and without the interposition of a receiving reservoir at the machine. The reduction in the hose diameter not only lengthens the life of the hose by saving the wear but materially reduces the cost as well. For example, in the described machine as actually constructed there was effected a reduction in hose diameter of from 2 in. to 1½ in.

The engine piston rods b² are each connected to a cross-head b³, the latter horizontally reciprocable in the cross-head guides b⁴ formed in the engine frame. The cross-heads are joined by the connecting rods b⁵ to the cranks b⁶, which are secured upon opposite ends of the crank shaft b⁷, which latter is mounted in boxes b⁸ and acts as the main driving shaft of the machine. The crank shaft being situated about midway the length of the machine and transversely thereof acts as the main power transmission shaft through suitable driving connections at one side to operate the cutting chain, and through suitably driven connections at the opposite side to actuate the feeding mechanism.

Referring first to the cutter chain and its driving mechanism, the cutter chain (shown in Fig. 1 but for the sake of clearness not in the other views) is mounted to travel along opposite sides of the cutter bar D, the latter having a swiveled support upon the machine. At the outer end of the cutter bar there is provided (Fig. 1) an idle sprocket wheel d over which the chain passes and at its inner end the driving sprocket wheel d' (Figs. 2, 3 and 5) through which the chain is driven, the driving sprocket wheel being mounted co-axially with the swiveling of the cutter bar.

The idle sprocket wheel d is mounted in a slide plate d², which through the adjusting screw d³ may be advanced upon the bar and clamped in a new position to take up wear in the cutter chain. The cutter bar except as hereinafter referred to, as well as the cutter chain, may be of any suitable or usual construction.

The inner or rear end of the cutter bar (Fig. 2) is provided with a removable cap d⁴ by which it may be clamped above its pivotal support b¹⁰ upon the bottom plate A.

The support b^{10} (Fig. 3) is in the form of a flanged sleeve firmly riveted to and within the bottom plate A, there being provided a necked portion b^{11} between which and the bottom flange the cutter bar has a swinging movement about the removable lining or bushing b^{12} . The sleeve b^{10} is also provided with an interior cup-shaped bushing b^{13} shouldered at its upper end and providing a lower step bearing for the upright sprocket wheel driving shaft E. The sprocket wheel d' is fast on the hub of the beveled gear e by which it is driven during cutting. The gear e is keyed to the shaft E, and the latter has in addition to the lower step bearing below the sprocket wheel also an upper journal bearing f , which is formed in the upper frame plate F. This provides an ample bearing surface for the driving sprocket wheel both above and below the chain, giving an extremely rigid construction for this type of machine.

The frame plate F, which is rigidly constructed, is provided with an up-raised lip or flange f^2 which incloses the interior operating parts and at its inner end has a transverse ledge or shoulder f^3 by which it is securely bolted (as shown in Fig. 1) to the upright support b^3 on the engine frame. At its outer end on the opposite side from the cutter bar it is supported on the corner of the bottom plate A through the pillar f^4 . The bevel gear e and other transmission parts carried by the frame plate F overlying the chain are protected against the entrance of the cuttings or dust by the cover or plate f^5 which is bolted to the frame plate. This leaves an open space across the machine between the bottom plate and the upper frame plate sufficient to pass the cutters and through which the cuttings may be carried. It also permits the cutter bar to be swung from a position transverse the machine (as shown in Fig. 1) through about 90° to a position aligned with the machine, where it may be most easily handled for mounting on its trucks.

The power is transmitted (Fig. 3) from the crank shaft b^7 to the sprocket wheel driving gear d' by means of the beveled pinion e' keyed to the longitudinal but inclined transmission shaft e^2 , the latter having fixed at its opposite end the beveled gear e^3 meshing with the bevel driving gear e^4 , the latter fixed upon the crank shaft.

It is frequently desirable to throw out of operation the cutting mechanism while still continuing the operation of the engine for driving the feeding mechanism, such occasion arising, for example, when it is desired to position the machine about the mine floor without cutting, or to load the machine on to its trucks. To permit the disengagement of the cutting mechanism there is provided means for throwing out of engagement cer-

tain of the intermediate transmission gears. In the present instance this is provided for by mounting the transmission shaft e^2 so that it may be swung upward about the crank shaft as a center and far enough to hold disengaged the beveled pinion e' from the beveled gear e . For this purpose the shaft e^2 is carried in a swinging gear frame G, forming in conjunction with the removable caps g journal boxes for the opposite ends of the transmission shaft, and provided with forked ends g^2 which pass below suitably formed shoulders on the boxes of the engine crank shaft. A forked cap g^3 for the forked portion of the swinging frame is provided so that the entire frame fits and swivels about the crank shaft boxes. The forward ends of the forks g^2 are slightly cut away to permit their application to or withdrawal from the crank shaft boxes. A cap G' covers the open portion of the gear frame and protects the gears from the entrance of dirt. The opposite end of the frame is held to a seat upon the frame plate F during engagement of the bevel gear e' with the gear e by a pin g^4 (shown in Fig. 21 and in dotted lines in Fig. 3) working in a longitudinal slot in the side of the swinging frame. The pin is connected to a crank g^5 (Figs. 1, 3, and 21), the center of which is provided with an out-turned squared head g^6 . The latter may be engaged by a wrench or other suitable implement and the crank thereby turned to raise or lower the pin. In its lowered position the frame is held down (as shown in Fig. 3) with the gears in engagement. In its elevated position it is held raised from its seat with the gears e and e' disengaged. This device for throwing the cutting mechanism out of gear is simple and adds substantially nothing to the height of the machine. At the same time it permits a very strong and solid sprocket wheel construction since the latter is fastened directly to its driving gear or to the driving shaft without the usual intervening clutch.

In the described machine I have provided means whereby the cutter bar may be swung to a position somewhat away from and at either side of a true right-angled relation to the machine. In Fig. 1 the cutter bar is inclined about 91° forward in the direction of cutting, which latter is shown by the arrow. This causes the bar to hold the machine to the coal as the machine is traversed without any special guiding devices other than the feeding chain, instead of being thrown away from the coal by the action of the cutters, as would be the tendency were the relation exactly right-angled. In this machine, which is adapted for cutting while the machine is traversed in either direction, there are provided means for locking the cutter bar with either the forward inclination shown in Fig. 1 or an opposite but like

inclination for the cutting in the reverse direction, as indicated in Fig. 6, the cutter chain and the inclination of the cutters being reversed when the direction of cutting is reversed.

Referring particularly to Figs. 1 and 5, the upper frame plate F is provided with a flanged portion f^6 which at the side of the machine is reinforced and provided with a pair of adjacent recesses or notches f^7 and f^8 . When the cutter bar is to be locked for cutting position a heavy latching bolt f^9 is inserted in one of the notches and the cutter bar swung about until the bolt passes through a registering aperture f^{10} of like formation in the cutter bar. The lower part of the latching bolt enters and is held by a similar notch in an underlying locking plate f^{11} secured to the upper edge of the bottom plate A. The two sets of notches in the upper frame plate and the underlying locking plate are so arranged that in co-operation with the latching pin they serve to lock the cutter bar in the correct position and with the proper inclination for cutting in either the one or the other direction. In addition to the latching bolt f^9 the cutter bar D may also be held fixed by the threaded bolt f^{12} (see Fig. 20), the latter, when placed in the aperture f^* , serving also to hold the cutter bar in its longitudinal position (not shown).

Although it is desirable to have means for reversing the engine in order to reverse the direction of cutting, the narrow width within which the long-wall machine must be kept makes it advisable to apply to the crank shaft the usual valve-reversing mechanism. In the machine herein shown I have provided means for reversing the engine which does not require the use of the usual eccentrics and eccentric connections. For this purpose (see particularly Figs. 1, 4 and 8 to 11 inclusive) there is provided a separate valve crank-shaft h , which has operative connection at opposite ends with the valve rods h' through the cranks h^2 and connecting rods h^3 . This shaft is driven from the driving pinion h^4 on the main crank-shaft b^7 and the intermeshing gear h^5 , the latter mounted on the valve shaft but adapted to turn the same through a suitable clutching device. For this purpose the gear is provided with a lateral lug h^8 (Fig. 4) which presents abutting surfaces for engagement on opposite sides with one or the other of the lugs h^9 or h^{10} , the latter extending laterally from the adjacent sleeve h^{11} pinned to the valve shaft h . During the operation of the engine the gear turning in the direction, for example, shown by the arrow in Fig. 9 turns the gear shaft in the same direc-

tion by engagement of its lug h^8 with the lug h^9 on the sleeve. If the engine is stopped it may then be reversed by merely turning the valve crank shaft ahead far enough to bring the lug h^{10} against the opposite face of the gear lug h^8 , as best shown in Fig. 10. This relative movement which is permitted between the two clutch members moves the valve mechanism either to an advanced or posterior position so that on opening of the engine throttle the engine starts up in a reverse direction, the gear then driving the valve shaft in the direction of the arrow shown in Fig. 10.

In order to prevent the valve shaft from overthrowing and reversing the engine during its operation the gear h^1 is slidable on the shaft and frictionally held against the face of the sleeve by the compression spring h^{12} . The frictional hold between the two clutch members, while sufficient to prevent the overthrow of the valve shaft, readily yields when the shaft is manually turned.

In order to turn the valve for reversal of the engine from without the outer casing I have provided the casing (see Figs. 7 and 8) with an opening having a hinged closure h^{13} opposite the valve shaft. This closure may be swung back and a key or wrench h^{14} (Fig. 11) inserted for turning the shaft. The key consists of a cylindrical roll fitting the aperture and having an inner slotted face at h^{15} which is adapted to engage the cylindrical end h^{16} on the crank shaft. By turning the outer squared end h^{17} on the key through a wrench or other suitable instrument the position of the valve shaft may be easily reversed.

The feed chain K is engaged by a driving sprocket wheel L (Figs. 4 and 14) which is driven through suitable connections from the crank shaft. When the machine is cutting in the direction of the arrow shown in Fig. 1 the chain is associated with the machine in the fashion there shown. That is to say, the leading end K' of the chain which is anchored to a fixed support in advance close to the face of the wall passes to the sprocket wheel, thence about an idler h at the side of the machine, thence along the outer side of the machine where it is guided by angle pieces h' to the opposite or rear end thereof, where it is also fixedly secured to a ratchet and pawl mechanism (not shown) by which the slack may be taken in or let out, as desired. The leading end of the machine is provided at its inner side with a guide roll h^2 , removably journaled on a stud at the corner of the machine. For this purpose there is bolted to the engine frame a bracket h^{14} having the outwardly directed, horizontal ear h^{15} . The latter is adapted to receive the stud h^2 which is screwed into the bed plate A, the stud having a squared head adapted to receive the

stud lock k^8 . This rolls along the face of the coal and acts to keep the machine body clear of the same and at a suitable distance therefrom. With the chain in this relation, 5 and particularly with the cutter bar slightly inclined forward, the machine is held up to the face of the wall about the sprocket wheel as a fulcrum by its own traversing action upon the chain. It will therefore be seen that this machine is capable of cutting 10 and feeding in either direction and that a change from a cut in one direction to a cut in the opposite direction may be made without turning or reversing the position of the machine as a whole,—an operation which, 15 on account of the narrow working space, is usually difficult or undesirable. When it is desired to cut in the opposite direction (Fig. 6) the guide roll k^2 is replaced by a brace rod k^3 , which together with a second brace k^4 extending to the opposite corner of the machine carries an idle sheave k^5 about which the chain passes from the sprocket wheel. The leading end of the chain which 20 is now that end adjacent to the cutter bar is carried over a second idle sheave k^6 journaled in removable brace bars clamped to the opposite corners of the machine, and thence to the anchor shown at s . The sheave k^5 , however, is located farther back 25 from the inner edge of the machine than the sheave k^6 , so that the draft on the chain now tends to hold the machine to the wall about the sheave k^6 as a fulcrum. In Fig. 6 the ratchet and pawl support for the chain is 30 shown at s' ; the direction of movement of the chain and the machine in Fig. 6 being represented by the arrows shown.

To position the machine about the floor 40 while it is doing no cutting it is desirable to have not only a slow cutting speed but also a higher speed under which the machine may be shifted from place to place under its own power, principally while the cutters 45 are inoperative. For this purpose the sprocket wheel L may be driven at will at either one of two speeds.

Referring particularly to Figs. 4 and 43, 50 the feed transmission gearing is driven primarily from an upright feed driving shaft l which has a lower step bearing l' upon the bottom plate A and an upper journal bearing in the plate M , the latter bolted to the engine casing. Movement is transmitted 55 from the crank shaft to the shaft l through a train of gearing comprising the beveled gear l^2 keyed to the shaft l and meshing with a beveled pinion l^3 , the latter rotated by the spur gear l^4 . The gear l^4 meshes directly with the counter-shaft gear h^5 . 60 Referring more particularly to Fig. 14 (not intended to be structurally accurate) 65 (not intended to be structurally accurate) driving movement is transmitted to the sprocket wheel L through the train of gearing as follows: The shaft l carries thereon

the pinion l^5 , to which driving movement is transmitted through an overhead yieldable transmission device hereinafter described. The pinion l^5 meshes with an adjacent gear m keyed to the upright on the high-speed driving shaft m' so that the latter is constantly rotated. Splined to the upper end of the shaft m' to rotate therewith is a sliding clutch sleeve or member m^2 having a toothed lower face which may be depressed to clutch with and drive the pinion m^3 , the latter having a toothed upper face. When thus clutched the pinion m^3 is caused to drive directly the main sprocket wheel driving gear h^6 which is keyed fast to the extended hub of the sprocket wheel L , the latter being journaled upon the fixed sprocket wheel stud l^7 .

For obtaining the slow feeding movement the constantly rotating clutch member m^2 has gear teeth m^4 which mesh with the large intermediate gear l^8 , the latter loosely journaled on the sprocket wheel shaft. The gear l^8 has secured to it the smaller overhead pinion l^{10} , which meshes with an idle gear l^{11} , the latter driving the larger gear n , which is loosely journaled on the upright, slow-speed, driving shaft n' . The gear n , being constantly driven at a reduced rate of speed, may be clutched to drive the shaft n' by depression of the sliding clutch member n^2 , the latter, on depression, having toothed engagement with the upper face of the gear hub. When thus clutched the shaft n' drives the pinion n^3 keyed thereto and through the pinion, which meshes with the main sprocket wheel driving gear h^6 , also drives the sprocket wheel L at a relatively slow rate of speed. In other words, with the clutch member m^2 raised and the clutch member n^2 lowered the sprocket wheel is driven at the slow or cutting speed. With the clutch member m^2 depressed and the clutch member n^2 raised the sprocket wheel is then driven at its higher or positioning speed.

To obtain different speed reductions at the slow speed the gear plate or frame O may be removed, the pinion l^{10} replaced by another and pinion l^{11} adjusted to a fresh position. For this purpose pinion l^{11} is carried upon a clamping stud adjustable about an arched slot o in the frame O (see Fig. 1), and pinion l^{10} has merely an interlocking engagement with the gear l^8 .

For engaging or disengaging the clutch members at will there is provided a sliding controlling rod (Fig. 15) o having suitably formed cam grooves o^1 in its face, which grooves are caused to engage lugs o^2 and o^3 , 125 respectively, carried by the sliding clutch members n^2 and m^2 . The lugs o^2 and o^3 are formed respectively upon sleeves o^4 and o^5 and these sleeves are retained, each upon a necked portion of its respective clutch 130

member, by flanged threaded caps o^6 and o^7 . The formation of the cam grooves is such that when the rod is moved to the left (as shown in Fig. 14) the clutch member m^2 is 5 depressed and the clutch member m^2 raised, giving the slow cutting speed. When moved to the right, the reverse condition takes place, giving the high speed. The rod o slides in guide-ways formed in the top of 10 the plate O , and is moved in one direction or the other by the hand lever o^8 (see Fig. 1) pivoted to the plate and having its end engaging a notched portion o^9 in the top of the rod.

16 In order to prevent excessive strain upon the feeding chain during cutting, there is interposed between the upright driving shaft l and the sprocket wheel a yieldable transmission device which permits slippage 20 when the safe load for the feeding chain is exceeded. This comprises a cup-shaped driven member p which is keyed to the driving pinion l^8 and has a cone-shaped friction surface engaging with a driving 25 member p' , which latter is splined to the driving shaft but free to slide lengthwise the same. During cutting these two members are pressed together by a spring p^2 seated in a pocket in the driving member p' , 30 the pressure of said spring being regulated by the adjusting nut p^3 , which of course is set to the degree required for transmitting the desired load.

In moving the machine about at the 35 higher speed, to avoid slippage at the transmission device, there is provided means for placing pressure upon the transmission device in addition to that of the spring. For this purpose there is threaded on the upper 40 end of the driving member p' a nut p^4 which retains a washer p^5 , between which and a shoulder on the driving member there is formed a grooved recess into which enter a pair of diametrically opposite pins p^6 45 (Fig. 12) carried by the swiveled ring frame p^7 , the latter being pivoted at p^8 upon the frame. The opposite end of the ring frame lying the other side of the transmission member has a forked portion p^9 carrying 50 the two upright adjusting screws p^{10} , between which works the cam roll p^{11} , the latter carried by the cam shaft p^{12} . By turning the hand lever p^{13} at the end of the cam shaft the cam roll may be turned to 55 raise or lower the ring frame, and therefore detract from or add to the pressure already exerted by the spring p^2 . By merely depressing the ring frame through the handle p^{13} the transmission device may be made to 60 transmit the desired load at the high speed and without slippage.

In order to prevent pressure in addition to that of the spring from being placed upon the transmission device during the cutting speed, the cam shaft p^{12} (Fig. 14) may

be provided with a lug p^{14} which, in the low speed position of the slide rod o , is caused to underlie an overhanging lug p^{15} carried by said rod. This prevents movement of the cam shaft in a direction to increase the pressure on the transmission device when the machine is traveling at the slow cutting speed.

For the actual operation of the machine in the mine there is provided a casing or enclosure, preferably of sheet iron, which incloses the principal working parts. Referring to Fig. 7 this, it will be seen, comprises a hinged top plate or cover r , which rests flush upon the upright lip or flange f^2 75 which encircles the upper frame plate, side pieces r' passing to the side of the engine frame, and an upper plate r^2 covering the engine frame, the whole comprising a substantially complete inclosure for the working parts, such as the transmission gearing journal boxes and the shafts. Reference to Fig. 18 will show the relation of the exhaust passages of the cylinder to the inclosing casing, the arrangement for the other cylinder being similar. At its head-end each cylinder exhausts through an exhaust port t controlled by the piston valve t' attached to the valve rod h' and connected with the outwardly directed exhaust passage t^2 which 80 opens directly into the atmosphere. At its opposite or crank end, however, the exhaust from the cylinder passes through a port t^3 85 also controlled by the valve t' , but connected with an exhaust passage t^4 which opens directly into the space inclosed by the outer casing. This casing, therefore, inclosing as it does the engine exhaust, receives the exhaust pressure from both engine cylinders 90 so that there is maintained within the casing a pressure somewhat in excess of the pressure of the surrounding atmosphere and, through the cracks or crevices at the joints of the casing, which need not be air tight or even approximately air tight, there 100 issues from within a steady stream of escaping air. This makes it practically impossible for any of the dust from the fine cuttings to enter the casing and to come in contact with the running parts. The protection of the operating parts of a mining engine in this fashion is an important advantage, it being possible with an engine of this type to run for long periods without giving attention to the bearings. The space beneath 105 the hinged cover r , partitioned off as it may be from the rest of the machine, may, if desired, be used as a receptacle for tools or the like.

110 It will be observed that the design of the individual mechanisms and parts, and particularly the compact relative arrangement of the said mechanisms and parts, provide a machine at once of remarkably low height 115 and narrow width, which are two important 120 factors in the use of such a machine in a 125 mine.

considerations in a machine of this type. This advantage, moreover, is obtained without sacrifice of efficiency or strength but, on the contrary, is accompanied by marked constructional and functional superiority.

5 While I have described and shown one form of my invention as embodied in one particular type of mining machine, it is to be understood that not only as to constructional details and form and relative arrangement of parts, but as to the embodiment or application made of various features of my invention, extensive modifications and departures from the described 10 form may be had.

15 Claims:

1. A mining machine having cutting means, a fluid-pressure motor for operating the same, transmission gearing, and a casing 20 inclosing the transmission gearing, said motor having connections with said casing whereby the latter receives the motor exhaust, and said casing being sufficiently imperforate to maintain a pressure therein in excess of the pressure of the surrounding atmosphere to prevent the entrance of dust or dirt thereinto.

2. A mining machine having cutting means and power transmission devices, an 30 inclosure for the power transmission devices, and means for producing a pressure in said inclosure in excess of the surrounding atmosphere to prevent the entrance of dust or dirt thereinto through the joints or openings thereof.

3. A mining machine having a bottom plate or shoe, means to cause travel of the machine in either direction along the mine upon said plate or shoe, a cutter bar and 40 means to fix the cutter bar laterally upon the shoe and at a forward inclination relatively to the line of advance of the machine.

4. In a mining machine, the combination with means upon which the machine is supported for sliding movement along the mine bottom, of means to traverse the machine in either direction, a cutter bar, and means to adjust the cutter bar laterally upon the supporting means and at a forward inclination 50 relatively to the line of advance of the machine in either direction.

5. In a mining machine, the combination with means upon which the machine is supported for movement along the mine bottom 55 in either direction, of flexible guiding means for holding the machine to its work during the cutting operation, the same connected to a fixed support on the advancing side of the machine and on the receding side thereof, and connected to the machine at one side near the wall or cutting end, and at the other side relatively near the opposite end thereof when traveling in either direction, a cutter bar, and means to fix the cutter bar laterally 60 upon the machine at a forward inclination

relatively to the line of advance of the machine, irrespective of the direction of travel.

6. In a mining machine for cutting in either direction, the combination with supporting means upon which the machine is adapted to slide along the mine, of flexible guiding means connected to a fixed support on the advancing side of the machine and on the receding side thereof, and connected to the machine at one side near the wall or cutting end and at the other side relatively nearer the opposite end thereof when traveling in either direction, a cutter bar pivoted on the machine and means for holding the same during cutting laterally and forwardly inclined relative to the line of travel irrespective of the direction thereof.

7. A mining machine having an upper and a lower frame member, a cutter bar swiveled between the upper and lower frame members, and a locking device for locking the said bar in any one of a plurality of positions.

8. A mining machine having an upper and a lower frame member, a cutter bar swiveled between the upper and lower frame members, and locking means to fix said cutter bar at either side of a right-angled relation to said machine.

9. A mining machine having an upper and lower frame member, means for traversing said machine, a cutter bar swiveled on the frame, said frame having a pair of recesses and said bar having an aperture adapted to register with either of said frame recesses, and a locking member adapted to pass through a recess in said frame and the aperture in said bar to lock the latter in position, the recesses in said frame being so located as to fix the bar during the machine traverse slightly offset from a right-angled relation to the machine.

10. A mining machine having an upper frame member, a lower frame member, a cutter bar swiveled between said lower frame member and the overlying end of said upper frame member, and locking devices for fastening the cutter bar slightly to one side of a right-angled relation to the machine.

11. A mining machine having an upper frame member, a lower frame member, a cutter bar swiveled between the upper and lower frame members and locking means for locking the cutter bar in any one of a plurality of positions to which it may be adjusted about its swivel support.

12. A mining machine having a bottom plate or shoe on which the machine is adapted to slide along the mine bottom, a cutter bar, a swiveling support for the cutter bar carried by and upon said bottom plate, and means for rigidly locking said cutter bar in a lateral relation to said machine.

13. A mining machine having a bottom plate or shoe, a cutter bar swiveled directly

- upon and above said shoe and a locking bolt for locking said bar at either side of a right-angled relation to the machine.
14. A mining machine having a bottom plate or shoe, an upper frame member, a cutter bar swiveled between the shoe and the upper frame member and means engaging the cutter bar, shoe and frame member for locking said bar in any one of a plurality of positions.
15. A mining machine having a bottom plate or shoe, feeding means upon the machine, a flexible feeding device with which the same is adapted to engage to cause the travel of the machine along the mine bottom, a cutter bar swiveled upon the shoe and means for locking said cutter bar at either side of a right-angled relation to said machine.
16. In a mining machine, the combination with a shoe on which the machine is adapted to travel along the mine bottom, of a cutter bar mounted to swing upon and over the shoe, and means to lock the same to the shoe at either side of a right-angled position relatively to the direction of travel.
17. In a mining machine, the combination with a shoe on which the machine is adapted to slide along the mine bottom, of a cutter bar mounted to swing over and upon the shoe, and means to lock the cutter bar either in line with the greatest length of the shoe or at substantially right angles thereto.
18. In a coal cutting machine, a frame, a cutter bar pivoted thereon and held at an angle to its longitudinal axis, a driving wheel and a plurality of guide members upon the said frame, and a flexible member fixed upon opposite supports, in engagement with the said guiding members and the driving wheel so as to cause, by rotation of the latter, linear movement of the frame between the said supports.
19. In a coal cutting machine, a frame, a cutter bar pivoted thereon and held in alignment with its longitudinal axis, a driving wheel and a plurality of guiding members upon the said frame, and a flexible member fixed upon opposite supports in engagement with the guiding members and the driving wheel, so as to cause by rotation of the latter, lateral movement of the frame.
20. In a mining machine, the combination with supporting means upon which the machine is adapted to slide along the mine, flexible guiding means connected to a fixed support on the advancing side of the machine and on the receding side thereof and connected to the machine at one side near the wall or cutting end and at the other side relatively near the opposite end thereof, a cutter bar pivotally mounted upon the said machine, and means for fixing the cutter bar in different positions thereon.

21. In a coal cutting machine, a substantially rectangular frame, comprising two superposed members, a cutter bar pivotally mounted in proximity to its foremost side, a driving wheel upon the frame, guiding members arranged in adjacency to the corners of the said frame, guiding members in proximity to the rearmost corners of the frame, and a flexible member engaging the driving wheel and one or more of the guiding members.

22. A mining machine having a bottom plate or shoe upon which the machine is adapted to slide along the mine bottom, a cutter bar pivotally mounted at one end of the plate, and a housed-in portion at the opposite end of the machine inclosing the power transmission members, said machine having an open space on either side of the cutter bar to permit the passage of the cuttings through the machine.

23. A mining machine having a bottom plate or shoe upon which the machine is adapted to slide along the mine bottom, a cutter bar pivotally mounted at one end of the plate, and a housed-in portion both at the opposite side of said machine and above said cutter bar, said machine having an open space on either side of the cutter bar to permit the passage of the cuttings through the machine.

24. A mining machine having a bottom plate or shoe upon which the machine is adapted to slide along the mine bottom, and a cutter bar pivotally mounted at one end of the plate, said machine having an open space above the bottom plate or shoe and on either side of the cutter bar to permit the passage of the cuttings through the machine.

25. A mining machine having a bottom plate or shoe upon which the machine is adapted to slide along the mine bottom, a cutter bar pivotally mounted at one end of the plate and a housed-in portion above the cutter bar, said machine having an open space on either side of the cutter bar and above the bottom plate.

26. A mining machine having cutting mechanism and chain feeding mechanism, means for maintaining one end of said chain nearer the inner edge of said machine than the other end thereof and removable connections adapted for application to said machine during reverse cutting to reverse the relation of said chain ends.

27. A mining machine having cutting mechanism and chain feeding mechanism in combination with a fixed support on the front or leading side of the machine, and a fixed support on the rear side of the machine, a chain secured to said support, said chain passing from the support at the leading end about a fulcrum bearing near the inner edge of the machine and reversible connections for the chain for feeding in the

opposite direction and providing a similar fulcrum bearing for said chain at the opposite end of the machine.

28. A mining machine having cutting mechanism, feeding mechanism, a flexible feeding member with which said feeding mechanism is adapted to engage, said member being connected to the machine at one side near the wall or cutting end and at the other side near the opposite end, and removable connections adapted for application to the said machine during reverse cutting to reverse the relation of said flexible feeding member to the machine.

29. A mining machine having cutting mechanism and feeding mechanism in combination with a fixed support on the front or leading side of the machine, and a fixed support on the rear side of the machine, a flexible feeding member secured to said support, said member passing from the support at the leading end to a fulcrum bearing near the inner edge of the machine and means for reversing the connection of the feeding mechanism for feeding in the opposite direction and providing a similar fulcrum bearing for said member at the opposite end of the machine.

30. The combination with a mining machine, of cutting mechanism, flexible guiding means for holding the cutting mechanism to the work, the same being connected to a fixed support on the advancing side of the machine and on the receding side thereof, and connected to the machine, on one side near the wall or cutting end and on the other side relatively near the opposite end thereof, and adjustable connections for reversing the relation of the said guiding members to said machine during reverse cutting.

31. In a mining machine, the combination with a cutting member carrying cutting mechanism comprising a cutter bar, sprocket wheel and cutter chain, and maintained at substantially right angles to the line of travel of the machine, driving mechanism for said cutting mechanism, feeding mechanism to cause travel of said machine during cutting, means upon which the machine is supported for sliding movement along the mine, flexible guiding means for holding the cutting mechanism to the work during the travel of the machine, and means for reversing the action both of the cutting mechanism and the feeding mechanism to cut and feed in the opposite direction.

32. The combination with a mining machine, of cutting means, feeding means, a shoe upon which it is adapted to slide along the mine bottom, flexible guiding means for holding the machine to its work during travel, the same connected to a fixed support on the advancing side of the machine and on the receding side thereof, and connected

to the machine at one side near the wall or cutting end and at the other side relatively nearer the opposite end thereof, and devices permitting the operation of the machine for cutting and feeding in either direction.

70

33. A long wall mining machine having a bed plate or shoe upon which it is adapted to slide along the mine bottom, flexible guiding means for holding the machine to its work during the cutting operation, the same presenting two flexible portions connected each to a fixed support one on the advancing side of the machine and the other on the opposite side thereof and one connected to the machine near the wall or cutting end and the other near the opposite end thereof, cutting mechanism and feeding means engaging said guiding means, the connections of said flexible guiding means to said machine being reversible whereby its relation may be reversed and the driving mechanism caused to drive the machine to cut in either direction.

75

34. A long wall mining machine having supporting means upon which the machine is adapted to slide along the mine bottom, flexible guiding means for holding the machine to its work during the cutting operation, the same presenting two flexible portions connected each to a fixed support one on the advancing side of the machine and the other on the opposite side thereof and one connected to the machine near the wall or cutting end and the other near the opposite end thereof, cutting mechanism and feeding means engaging said guiding means, the connections of said flexible guiding means to said machine being reversible whereby its relation may be reversed and the driving mechanism caused to drive the machine to cut in either direction.

80

35. A long wall mining machine having a cutter chain, a cutter bar carrying said cutter chain and mounted at substantially right angles to the line of travel of the machine, driving mechanism for the cutter chain, feeding mechanism to cause travel of said machine during cutting, supporting means for the machine, flexible guiding means engaging the machine at one side near the coal or cutting end and at the other side near the opposite end, the said cutting mechanism being reversible and the said flexible guiding means having reversible connections to the machine whereby both the cutting mechanism and the feeding mechanism may be reversed to cut and feed in the opposite direction.

90

36. In a long wall mining machine for cutting in either direction, the combination with suitable motive means, of a cutter bar presented laterally from the machine during the cutting operation, a cutter chain and sprocket wheels, supporting means adapted to slide along the mine bottom, flexible

guiding means connected to the machine at one side thereof near the wall or cutting end and at the other side near the opposite end when traveling in either direction, connections for causing the machine to travel and cut a continuous kerf in one direction and connections for causing the same at will to travel and cut a continuous kerf in the opposite direction whereby the machine 10 may be reversed without turning the same around.

37. A mining machine having a cutter chain and a cutter bar carrying the same, a bottom plate or shoe on which the machine 15 is adapted to slide along the mine bottom, and a swiveling support for said cutter bar rigidly fastened to and upon the said shoe.

38. A mining machine having a cutter chain, a swinging cutter bar therefor, a bottom plate or shoe on which the machine 20 is adapted to slide along the mine bottom, a swiveling support for said cutter bar rigidly fastened to said bottom plate, a driving sprocket wheel for said chain, and an upright sprocket wheel driving shaft having a step bearing in said swiveling support.

39. A mining machine having a cutter chain, a swinging cutter bar therefor, a driving sprocket wheel for said cutter chain, 30 and an upper frame member and a lower frame member furnishing a bearing support both above and below said sprocket wheel.

40. A mining machine having a bottom plate or shoe upon which said machine is 35 adapted to slide along the mine bottom, a cutter bar having a swiveled support, a cutter chain carried thereby, a driving sprocket wheel for said cutter chain, and a journal bearing for said driving sprocket wheel both above and below the same.

41. In a mining machine, the combination 45 with a bottom plate or shoe upon which the same is adapted to travel along the mine, of a cutter bar pivotally mounted for adjustment, a sprocket wheel and a cutter chain, said sprocket wheel having a bearing support upon the shoe.

42. In a mining machine, the combination 50 with a bottom plate or shoe, of a cutter bar, a sprocket wheel and cutter chain, the sprocket wheel having a bearing support on the shoe, and the cutter bar being swiveled upon said bearing support.

43. A mining machine comprising in 55 combination, a cutter chain, a cutter bar, a moving support, flexible guiding means for holding the machine to its work during travel, the same connected to a fixed support on the advancing side of the machine and on the receding side thereof, and connected to the machine at one side near the wall or cutting end and at the other side 60 relatively near the opposite end thereof, feeding means engaging said guiding means,

a reversible actuator for said cutter chain and said feeding means, and a plurality of guiding means engaging members, whereby said machine may cut and feed in either direction.

44. A mining machine comprising in combination, a cutter chain, a cutter bar, a moving support, flexible guiding means for holding the machine to its work during travel, the same connected to a fixed support on the advancing side of the machine and on the receding side thereof, and connected to the machine at one side near the wall or cutting end and at the other side 70 relatively near the opposite end thereof, feeding means engaging said guiding means, a reversible actuator for said cutter chain, and a plurality of guiding means engaging members, whereby said machine may cut and feed in either direction.

45. In a mining machine, the combination with cutting mechanism, of means for traversing the machine along the mine during the cutting operation, a pressure fluid motor on, and movable with, the machine 75 during cutting, and a flexible hose connection for supplying pressure fluid to the engine during the travel of the machine, said machine being provided with a pressure fluid reservoir also on the said machine and interposed between the motor and the flexible hose connection and of sufficient capacity 80 relatively to the capacity of the pressure fluid motor to maintain the supplied pressure substantially constant.

46. In a mining machine, the combination with cutting mechanism, of means for traversing the machine along the mine during the cutting operation, a pressure fluid motor on, and movable with, the machine 105 during cutting, and a flexible hose connection for supplying pressure fluid to the engine during the travel of the machine, said machine being provided with a pressure fluid reservoir also on the said machine and interposed between the motor and the flexible hose connection, and having a capacity 110 not less than the capacity of the pressure fluid motor.

47. The combination with cutting mechanism, of means for traversing the machine along the mine, a pair of pressure fluid engine cylinders arranged side by side upon the mining machine, and a pressure fluid receiving chamber between the two cylinders carried by said engine to move with the traveling structure of the machine during cutting, said chamber having a capacity not less than the combined capacity of the two cylinders.

48. The combination with cutting mechanism, of means for traversing the machine along the mine, a pair of pressure fluid engine cylinders arranged side by side upon the mining machine, and a pressure fluid 120

receiving chamber between the two cylinders carried by said engine to move with the traveling structure of the machine during cutting, said chamber having a capacity not less than the capacity of one of the said cylinders.

49. A mining machine having a bottom plate or shoe upon which the machine is adapted to slide along the mine bottom, a fluid-pressure engine mounted at one end of said bottom plate, a cutter bar with its supported cutter chain pivotally mounted at the opposite end of said plate, a crank-shaft between the engine and the cutter bar support, and transmission gearing between said crank-shaft and said cutter bar.

50. A mining machine having a bottom plate or shoe upon which the machine is adapted to slide along the mine bottom, a fluid-pressure engine mounted at one end of said bottom plate, a cutter bar with its supported cutter chain pivotally mounted at the opposite end of said plate, a crank-shaft between the engine and the cutter bar support, transmission gearing between said crank-shaft and said cutter bar, and feed transmission gearing between said engine and said crank-shaft.

51. A mining machine having a fluid-pressure engine mounted at one end thereof, a cutter bar with its cutter chain at the opposite end, a bottom plate or shoe underlying the cutter bar, a driving sprocket wheel for the cutter chain, an upright sprocket wheel driving shaft, a beveled gear upon said driving shaft, a crank shaft driven from the engine, and a longitudinal transmission shaft provided with beveled gears for transmitting power from the crank shaft to the sprocket wheel and driving shaft.

52. A mining machine comprising in combination, a cutter chain, a cutter bar, a moving support, flexible guiding means for holding the machine to its work during travel, the same connected to a fixed support on the advancing side of the machine and on the receding side thereof, and connected to

the machine at one side near the wall or cutting end and at the other side relatively near the opposite end thereof, feeding means engaging said guiding means, and an actuator for said cutter chain and said feeding means, reversing means for said cutter chain, and a plurality of guiding means engaging members, whereby said machine may cut and feed in either direction.

53. A mining machine having a cutter bar, a cutter chain, a sprocket wheel for the cutter chain, a main power transmission shaft, and intermediate gearing between said transmission shaft and said sprocket wheel, including a swinging transmission shaft whereby said gear may be thrown out of engagement.

54. A mining machine having a cutter bar, a cutter chain, a sprocket wheel for the cutter chain, a bevel driving gear for said sprocket wheel, a driving pinion engaging said bevel gear, and a swinging transmission shaft on which said pinion is mounted whereby said pinion and gear may be engaged or disengaged at will.

55. A mining machine comprising, in combination, a cutter chain, a cutter bar, a flexible advance feeding and guiding member engaging a fixed support in advance of the machine and engaging the machine at a point near the wall or cutting end thereof, a flexible rearwardly extending drag line member engaging a fixed support in the rear of the machine and engaging the machine at a point adjacent the opposite end of the machine from said wall or cutting end, an actuator, means for reversing said cutter chain, and means for operatively reversing the engagements of said flexible members, whereby the machine may cut and feed laterally in either direction.

In testimony whereof, I have signed my name to this specification, in the presence of two subscribing witnesses.

ALBERT BALL.
